UNITED STATES PATENT OFFICE.

WILLIAM P. STEWART, OF NEW YORK, N. Y.

TOY KNITTING-MACHINE.

SPECIFICATION forming part of Letters Patent No. 289,578, dated December 4, 1883.

Application filed June 24, 1880. (No model.)

To all whom it may concern:

Be it known that I, WILLIAM P. STEWART, of the city, county, and State of New York, have invented a new and useful Improvement 5 in Toy Knitting-Machines, of which the following is a specification.

This invention relates to those means of affording instructive and amusing knitting employments to children which have heretofore 10 found expression in the use of a wooden spool, perforated cork, or other similar body, in one end of which pins or tacks set together in pairs to serve as single knitting-points, or pieces of wire shaped as staples to serve the 15 same purpose, would be driven, and on these a worsted thread or yarn would be so crossed or laid and manipulated with the aid of a pin or other pointed instrument as to produce a variety of simple fabrics in the shape of flat 20 or round webbings, the projecting heads or rims of the pins or tacks or the outwardly-inclined tops of the wire staples serving in a manner to hold the newly-laid yarn in position, while the space between the two pins or 25 tacks or the two arms of the staple employed as a single knitting-point afforded the necessary facilities for introducing the point of the picker under the formed loop in the act of lifting over, as required in picker-knitting.

30 The invention comprises novel combinations and relationships of parts, all of which will be hereinafter described, and then pointed out in the claims.

In the accompanying drawings, in which 35 similar letters of reference indicate like parts, Figure 1 is a perspective of a device embodying my invention. Fig. 2 is a vertical longitudinal section of the same; and Fig. 3 is a detailed view of the revolvable plate having attached the knitting-points. Fig. 4 is a further detailed view of the knitting-plate in blank, and Fig. 5 is a more distinct view of the tension-post provided with the guides.

A is a revolvable knitting plate or disk, with 45 the knitting-points C fastened to or raised from itself.

B is a body, to which the tension-post H is attached, and on which the revolvable plate A is made to rest, as shown in Fig. 2.

50 C C C are knitting-points so shaped and

raised as to securely hold the free yarn while the under-formed loop is being carried over in the process of knitting, as shown in Fig. 1. The special features of this point consist in its being fashioned from the same piece of metal holding it in position, in its having an open or perforated body, which admits of the easy introduction of the picker-point for the purpose of gathering the under-formed loop and lifting it over the newly-laid yarn, and in the forward and peculiar curve of the point, which forms a half-circle, bringing the upper end in a direction pointing downward, thus forming a kind of hook, which effectually holds the yarn and renders feasible more difficult forms of looping than would be practicable with a point not having this feature.

H, Fig. 1, is the part forming the tension-post, and provided with the guides. This is made of wire, preferably. The tension is 70 formed by taking one or more winds of the yarn around the body of the post before passing it through the guide. The guides are formed by simple turns of the wire, forming the body of the post.

D is a small circle thus formed, and designed as a guide for the yarn or other substance taking the form of knitted loops, and when this is in proper position the yarn is laid directly under the curled tops of the knitting-points.

E is a larger circle, formed in the same manner, and is designed to guide any fabric—as, for instance, a cord—which it may be desirable to cover with the looping yarn. 85 When in proper position, this guide is so far above the knitting-points as to feed over them instead of on them, as in the case of guide D. This is necessary in order to keep the cord from becoming entangled with the knitting-points in turning.

f f, Fig. 1, show the true shape and curve of the knitting-point at the upper end, and J the character of the perforation in the body.

G, Fig. 1, is a simple form of the picker 95 necessary to and employed with the machine in the process of knitting.

I shows a cord introduced through the guide E in the process of knitting around it. P shows the cord dropping below the machine 100

with the yarn covering, and Q shows the yarn as fed without a tension through the guide D.

In operation my invention is to be held lightly in the left hand or fastened to any convenient rest by any suitable contrivance. The 5 yarn is to be fed from the back of the hand or rest through the guide D, and the cord through the guide E, and the knitting-plate turned to the right with the formation of each new loop, 10 which is made, in manner as heretofore done in picker-knitting, by means of a pick held in the right hand.

The process of knitting may be varied by carrying the yarn laid twice over each knitting-point, or by looping several times over the one point before turning to the next, or by reversing the direction in which the knitting- 15 plate is revolved.

What I claim as my invention is—

20 1. The revolvable knitting plate or bed A, provided with two or more knitting-points, in combination with stationary guides and a

stationary holder or body, substantially as described.

2. The combination, with the body B and 25 the picker G, of the plate A, provided with the flat perforated knitting-points C, raised and fashioned therefrom, substantially as described.

3. The combination, with the body B and 30 the picker G, of the revolvable plate A, provided with the knitting-points C, having flat perforated bodies, and the tips of their upper ends curved outward and downward in the form of a half-circle, substantially as described. 35

4. The combination, with the body B and plate A, provided with the knitting-points C, of the picker G and the tension-post H, provided with the small ring D and the larger ring, E, substantially as described.

WM. P. STEWART.
